UNITED STATES PATENT OFFICE.

WILLIAM BARTHOLOMEW, OF CHICAGO, ILLINOIS, ASSIGNOR TO TROY LAUNDRY MACHINERY COMPANY, LTD., OF CHICAGO, ILLINOIS, A CORPORATION OF NEW YORK.

DRYING APPARATUS.

1,189,777.

Specification of Letters Patent.

Patented July 4, 1916.

Application filed August 28, 1914. Serial No. 859,036.

To all whom it may concern:

Be it known that I, WILLIAM BARTHOLOMEW, a citizen of the United States, residing at Chicago, in the county of Cook and State of Illinois, have invented certain new and useful Improvements in Drying Apparatus, of which the following is a specification.

My invention relates in general to drying apparatus, and more particularly to drying 10 tumblers for laundry use.

Drying tumblers of the character to which my invention relates comprise a rotary foraminous cylinder inclosed within casings containing steam-heated coils, and a blower 15 for circulating air around the coils and thence through the foraminous cylinder to dry the articles therein. It has usually been customary in such dry room tumblers to discharge the heated air after being once circulated around the heating coils and through 20 the rotary cylinder. This is wasteful of heat and unnecessarily prolongs the drying operation, as, obviously, only a limited degree of heat can be imparted to the air by merely 25 passing once around the heating coils. However, to circulate the same air repeatedly by the blower around the heating coils and through the cylinder involves difficulties, as the air in passing through the articles in 30 the cylinder becomes laden with lint which accumulates in the blower and produces an unbalanced condition thereof, resulting in excessive wear and injury.

The primary object of my invention is to 35 provide in a drying tumbler, of the type in which the heated air is repeatedly circulated through the articles to be dried, improved mechanism for automatically eliminating lint, or other particles of material, 40 from the air before it again passes through the blower, thereby protecting the blower from injury.

A further object of my invention is to 45 provide a drying tumbler in which the lint picked up by the air in passing through the articles will not only be eliminated from the air, but will be automatically removed from the apparatus, so as not to impede the repeated free circulation of the hot air through 50 the articles.

A still further object of my invention is to provide a drying tumbler which will be simple in construction, efficient in operation, and convenient in use.

My invention will be more fully disclosed 55 hereinafter with reference to the accompanying drawings, in which the same is illustrated as embodied in convenient and practical form, and in which—

Figure 1 is a front elevational view, parts 60 being broken away. Fig. 2 is a sectional view, taken on the line 2—2 of Fig. 3; and Fig. 3 is a vertical sectional view.

The same reference characters are used to 65 designate the same parts in the several figures of the drawings.

Reference characters A', A² designate the end-supporting frames of a casing or housing, such frames being preferably made of cast metal and provided with pairs of feet 70 a' and a² at the lower edges thereof, which serve to support the casing. Secured to the inner surfaces of the end frames A' and A² are sheet metal plates A which form the end 75 walls of the casing.

B designates the front wall of the casing, which is preferably formed of sheet metal and supported upon the front surfaces of the end frames. The upper portion of the front wall B is curved to conform to the 80 curvature of a cylinder C, supported in the casing by suitable trunnions journaled in the end frames. The cylinder is of any suitable construction, so as to permit the free passage of air therethrough, and may 85 conveniently be formed of wire fabric supported upon a suitable frame. The upper curved portion of the front wall B is provided with a hinged door B', preferably of a width coextensive with the width of the 90 cylinder C, while the latter is provided with a similar hinged door C', so that when the doors are brought in registry articles may be placed in, or removed from, the cylinder. One of the trunnions of the cylinder C projects through one of the side frames, as 95 shown in Fig. 1, and is provided with suitable means for imparting rotary motion thereto, such, for instance, as belt pulleys D.

E designates the rear wall of the casing, 100 which is provided with an inclined top portion E' extending above the cylinder C and connected with the top edge of the curved upper portion of the front wall B by means of a downwardly curved portion e'.

F designates a substantially semi-circular partition extending from one end wall to the other end wall and closely surrounding the

5 rear and bottom surfaces of the cylinder, as clearly shown in Fig. 3. The top edge of the partition F terminates a short distance from the top edge of the upper curved portion of the front wall B to form a passage-way immediately above the cylinder, and preferably coextensive therewith.

10 G designates a partition extending downwardly from the rear surface of the curved partition F to the bottom wall J of the casing. The partition G is spaced inwardly from the rear wall of the casing, so as to provide a chamber in which are located heating coils H, through which passes a heating 15 medium, such as steam.

20 K' and K² designate blowers supported upon the bottom wall J of the casing beneath the semi-cylindrical partition F and having their discharge openings communicating with openings through the partition G adjacent the bottom thereof, as shown in Fig. 3.

25 K designates a shaft upon which the blades of the blowers are secured, and by means of which they are rotated. This shaft is journaled in bearings on the end walls of the casing, one end of the shaft projecting through one of the end walls, as, for instance A², and being provided with suitable power connections for rotating the same.

30 L designates a cylindrical screen mounted within the casing intermediate of the cylinder C and the intakes of the blower K' and K². The cylindrical screen is mounted upon 35 a concentric rod l, which is journaled at its ends in the end frames A' and A² of the casing. One end of this rod is provided with suitable means for rotating the screen.

40 Located adjacent the cylindrical screen L is a rotary brush M, which is provided at its ends with trunnions m journaled in the end frames of the casing. This brush comprises spirally arranged strips M' of flexible material, such, for instance, as felt, which 45 strips bear against the outer surface of the cylindrical screen. A trough N is located beneath the brush M and partially surrounds the same, said trough extending from one end wall of the casing to the other, and being 50 provided with a spout portion N' at one end extending through an opening in one of the end walls, as, for instance, A', of the casing A. One wall of the trough extends upwardly into contact with the inner surface 55 of the front wall B of the casing, as indicated at n. The inner wall of the trough projects upwardly into contact with the lower surface of the cylindrical screen, and is provided with one or more strips o' and o² 60 of flexible material, such, for instance, as felt, which bear against the screen throughout its length.

65 The screen L and brush M are preferably rotated in opposite directions by any suitable means, as, for instance, a belt L' en-

gaging a pulley l' fixed to the end of the rod l which projects through the end wall A² of the casing, said belt also engaging a pulley m' fixed to the trunnion m of the rotary brush M which projects through the end wall A² of the casing. The brush may be rotated in any suitable manner, as by means of a pulley M² fixed upon the upwardly projecting portion of one of its trunnions m, engaged by a belt m² passing around a pulley k' fixed upon the correspondingly projecting end K of the shaft of the fans K' and K².

70 In order to insure the air passing from the cylinder C through the rotary screen L before it is drawn into the blowers, a strip f' of flexible material, such, for instance, as felt, is secured to the lower edge of the partition F and bears against the adjacent surface of the screen, as clearly shown in Fig. 3.

75 The manner of using and operation of my improved drying tumbler are as follows: The door C' of the cylinder C is brought into registry with the door B' at the front of the casing, so that both of the doors may 80 be opened and wet articles placed within the cylinder to be dried. The doors are then closed, and the cylinder rotated through the power connections so as to agitate the articles and expose all portions 85 thereof to the circulating hot air. The fans are rotated, through suitable connections, so as to force air into the bottom of the heating chamber containing the steam-heated coils H. The air passes around the 90 steam-heated coils and is heated thereby, after which it passes through the opening above the cylinder, thence through the cylinder into contact with the articles contained therein. The rotation of the blowers 95 draws the air from the cylinder through the portion thereof intermediate of the front wall of the casing and the lower edge of the semi-cylindrical partition F. The air thus drawn from the cylinder by the blowers 100 passes through the screen L which serves to remove from the air the lint, or particles of other materials, with which it is laden by reason of its passage through the articles in the cylinder C. The air then passes 105 through the intake openings of the blowers and is again delivered to the bottom of the heating chamber H to be reheated by passing upwardly around the steam-heated coils. The same air is therefore circulated continuously 110 through the cylinder, and after each passage therethrough passes through the cylindrical screen so as to have the lint removed therefrom. The consumption of heat is therefore economized and the drying 115 of the articles promoted, inasmuch as the air is successively reheated.

120 The relative rotation of the cylindrical screen L and the brush M causes the spirally arranged strips M' to remove from the ex- 125

terior of the cylinder all of the lint, or particles of other material, deposited thereon, such particles of material falling into the trough N, and being delivered therefrom through the spout N' to the exterior of the casing. The spiral arrangement of the strips upon the brush therefore serves as a screw conveyer to move the particles of material removed from the screen toward the outlet spout N'.

When the articles have been treated a sufficient length of time to thoroughly dry them, the door C' of the cylinder C is again brought into registry with the door B' of the casing, and the dry articles are removed, and another supply of articles to be dried placed within the cylinder.

From the foregoing description it will be observed that I have invented an improved drying tumbler in which the air is kept in circulation around the heating coils and through the cylinder, thereby economizing the heat and expediting the drying of the articles, and in which the lint, or particles of other matter, with which the air passing from the cylinder is laden, is eliminated from the air before it passes through the blowers and is automatically discharged to the exterior of the casing.

While I have described my invention with more or less minuteness, and as being embodied in certain precise forms, yet it will be understood that I do not desire to be limited thereto unduly, or any more than is pointed out in the appended claims. On the contrary, I contemplate all proper changes in form, construction, and arrangement, the omission of immaterial parts, and the substitution of equivalents as circumstances may suggest or render expedient.

I claim:—

1. In a drying tumbler, the combination with a casing, of a rotary cylinder in said casing for containing articles to be dried, a heating chamber, a blower for circulating air through the heating chamber and thence through the cylinder, a screen through which the air passes before being drawn through the blower, and means for automatically removing the particles of material deposited upon said screen.

2. In a drying tumbler, the combination with a casing, of a rotary cylinder in said casing for containing articles to be dried, a heating chamber, a blower for circulating air through the heating chamber and thence through the cylinder, a screen through which the air passes before being drawn through the blower, and a movable brush engaging said screen for removing therefrom particles of material deposited thereon.

3. In a drying tumbler, the combination with a casing, of a rotary cylinder in said casing for containing articles to be dried, a heating chamber, a blower for circulating

air through the heating chamber and thence through the cylinder, a screen through which the air passes before being drawn through the blower, and a rotary brush engaging said screen for removing therefrom particles of material deposited thereon.

4. In a drying tumbler, the combination with a casing, of a rotary cylinder in said casing, a heating chamber, a blower for circulating air through the heating chamber and thence through the cylinder, a screen through which the air passes before being drawn through the blower, and a rotary brush comprising pliable strips spirally arranged thereon engaging said screen to remove particles of material deposited thereon and to discharge the particles of material to the exterior of the casing.

5. In a drying tumbler, the combination with a casing, of a rotary cylinder in said casing, a heating chamber, a blower for circulating air through the heating chamber and cylinder, a rotary cylindrical screen for eliminating particles of material from the air after it passes through the cylinder and before it enters the blower, and means engaging the exterior of said cylindrical screen for removing therefrom particles of material deposited thereon.

6. In a drying tumbler, the combination with a casing, of a rotary cylinder in said casing, a heating chamber, a blower for circulating air through the heating chamber and cylinder, a rotary cylindrical screen for eliminating particles of material from the air after it passes through the cylinder and before it enters the blower, and a brush movable relatively to and engaging said screen for removing therefrom particles of material deposited thereon.

7. In a drying tumbler, the combination with a casing, of a rotary cylinder in said casing, a heating chamber, a blower for circulating air through the heating chamber and cylinder, a rotary cylindrical screen for eliminating particles of material from the air after it passes through the cylinder and before it enters the blower, and a cylindrical brush rotating relatively to and engaging said screen to remove therefrom particles of material deposited thereon.

8. In a drying tumbler, the combination with a casing, of a rotary cylinder in said casing, a heating chamber, a blower for circulating air through the heating chamber and cylinder, a rotary cylindrical screen for eliminating particles of material from the air before it passes through the cylinder and before it enters the blower, and a cylindrical brush rotating relatively to said screen, said brush comprising strips of pliable material spirally arranged thereon engaging said screen to remove particles of material deposited thereon and discharge the particles of material to the exterior of the casing.

9. In a drying tumbler, the combination with a casing, of a rotary cylinder in said casing, heating coils, a blower for circulating air around the heating coils and through the cylinder, a rotary cylindrical screen located intermediate of said cylinder and the intake of said blower, and means engaging the exterior of said cylindrical screen for automatically removing particles of material deposited on said screen.
10. In a drying apparatus, the combination with a chamber for containing the articles to be dried, of means for circulating heated air through said chamber, a rotary screen through which the heated air passes after passing through the articles in said chamber, and rotary means for automatically removing the particles of material deposited upon said screen.
11. In a drying apparatus, the combination with a chamber for containing the articles to be dried, of means for circulating air through said chamber, a rotary cylindrical screen for eliminating particles of

material from the air after it passes through said chamber, and a brush movable relatively to and engaging said screen for removing therefrom particles of material deposited thereon.

12. In a drying apparatus, the combination with a chamber for containing the articles to be dried, of means for circulating heated air through said chamber, a rotary cylindrical screen for eliminating particles of material from the air after it passes through said chamber, and a cylindrical brush comprising strips of yielding material spirally arranged thereon and engaging said screen to remove particles of material deposited thereon and discharge them to the exterior of the apparatus.

In testimony whereof, I have subscribed my name.

WILLIAM BARTHOLOMEW.
